(57) **CLAIM**

The ornamental design for a combined radiation thermometer and camera, as shown and described.

DESCRIPTION

FIG. 1 is a perspective view of the top, front and left side of a combined radiation thermometer and camera with the viewer in the open position showing our new design; FIG. 2 is a front view thereof;

FIG. 3 is a top view thereof;

FIG. 4 is a rear view thereof;

FIG. 5 is a right side view thereof;

FIG. 6 is a left side view thereof;

FIG. 7 is a bottom view thereof; and,

FIG. 8 is a view similar to FIG. 1 with the viewer in the closed position.
